UNITED STATES PATENT OFFICE

CHARLES A. UPSON, OF LOCKPORT, NEW YORK, ASSIGNOR OF ONE-HALF TO W. HARRISON UPSON, OF LOCKPORT, NEW YORK

MOISTURE-CONTENT TESTER FOR PAPER-MAKING MACHINES

Application filed August 26, 1926. Serial No. 131,778.

My present invention relates to the art of paper making, and more particularly to means for testing the moisture content of the paper as it progresses through or emerges 5 from the making machines, and it has for its object to provide a simple and efficient device of this nature that will accurately reflect the moisture content of the entire web, and from which the tender may frequently 10 and accurately determine the condition of the issuing web of paper and correct factors in the general operation of the machine which may be responsible for imperfections in the paper arising from imperfect moisture elimination. To these and other ends the invention resides in certain improvements and 15 combinations of parts, all as will be herein-after more fully described, the novel features being pointed out in the claims at the 20 end of the specification.

In the drawings:

Figure 1 is a side elevation of the dry end of a paper making machine fitted with a moisture content testing apparatus constructed in 25 accordance with and illustrating one embodiment of my invention;

Figure 2 is a transverse sectional view through the roll and hood shown in Figure 1.

Similar reference numerals throughout the several views indicate the same parts.

There are two parts to a paper machine, one usually called the wet end, where the fibers are formed into a web of paper by 35 screening them out of the water with which the pulp or stock is mixed and fed to the machine. This web is weak and flabby and contains a large percentage of water even after the greater portion has been expressed by 40 means of squeeze rolls. The other part of the machine is called the dry end toward which the web progressively proceeds and which receives the very wet web and dries it. The process of drying on all types of paper 45 machines is about the same, consisting of a few or a large number of dryers which are revolving steam heated cylinders. The paper coming from the wet end passes over the surfaces of the drying cylinders which drives 50 out the water in the form of vapor. The

cylinders are so arranged that both surfaces of the web of paper are alternately in contact with the heated dryer surface. This process is really the removal of water from the felted pulp, first by mechanical means of 55 squeeze rolls and then by the use of heated rolls, drawing out the water by evaporation. About two tons of water to one ton of paper is evaporated.

The finished paper web as it issues from 60 the machine still contains some moisture which is desirable to a certain extent and the proportion of which is varied according to the kind of paper being made and the uses for which it is intended. To properly proportion 65 this moisture content is very important.

For example, in making newsprint paper, it is important to have this paper dried at 70 about the average humidity of the air. If the newsprint is overdried, it is very unsatisfactory, causing breaks, delays in production and large waste in operating the modern high speed newspaper printing machines. On the other hand, it must be noted if newsprint paper is 75 too moist, calendering cannot be accomplished satisfactorily. These same faults are true of many other kinds and grades of printing paper. In the making of wrapping paper for illustration, if it is made too dry 80 it lacks strength, folding qualities and it is stiff and brittle. In the making of paper board products like boxboard and container stock, if the material is too dry it will not bend without breaking, and in an automatic 85 box making machine causes reduced output and loss. Again, in the making of pasted or laminated board as used for containers, if the stock is over dried the strength is reduced and board actually damaged. On the 90 other hand, if the product is too wet or contains wet streaks, the adhesive does not make a good bond of the plies causing a total loss or a weakened stock.

The vapor or moisture in the sheet of paper 95 we speak of as relative humidity, the relativity being that between the moisture content of the paper and the moisture content of the surrounding air when completely saturated. Such relative humidity is the ratio 100

between the quantity of vapor actually present and that which would be present if the air were saturated at the temperature of observation. Such relative humidity is usually expressed in percentage at seventy-five per cent which denotes that the air contains three-fourths of the water vapor required to saturate it at a given temperature. It is the existence of this relative humidity or plainly speaking, humidity of the air which makes it possible for us to utilize it in determining the moisture content of the sheet of paper running on the machine.

My present invention is addressed to the proposition of accurately recording this humidity and in doing so I take advantage of the use of the well known wet and dry bulb thermometer which is a combination ordinarily called a psychrometer. These instruments usually consist of two thermometers mounted side by side a short distance apart, one having a dry bulb and the other covered with muslin or cotton material kept moist by capillary action through conducting threads of lamp wicking from a very small reservoir of water. Thus the dry bulb indicates the temperature of the air itself, while the wet bulb cooled by evaporation shows usually a little lower temperature according to the amount and rapidity of evaporation. Hence the difference in temperatures of the two bulbs is the greatest when the air is driest. By experimenting, it has been ascertained the relative humidity corresponds to the degrees difference between the two thermometers for any given temperature of air. In other words, an observer reads the difference of temperatures in the two bulbs and from these two determines the relative humidity of the air. Knowing the relative humidity of the air and carrying out laboratory tests in obtaining the moisture content of a sheet, it is possible to establish a chart showing the moisture content of the sheet for all the variations in the relative humidity indicated by the instrument. If a definite relative humidity can be standardized on the machine for various grades of paper at a given caliper speed, it is possible for the machine operator to watch his recording chart attached to the psychrometer and know whether or not paper is being dried to the moisture content that is specified.

My method of obtaining an immediate and continuous record of the moisture content of a sheet of paper as it is drying or about to leave the machine in a finished condition is accomplished by placing one or more hoods over one or more of the drying rolls. If only one hood is used (and in many cases this is sufficient) it is important that such hood be placed over or around one of the last drying rolls to fit as closely to the paper as possible so that the machine operator is not inconvenienced and the threading of the sheet

around the dryer is not obstructed. Referring more particularly to the drawings, 1 indicates the frame of the dry end of a paper making machine upon which are mounted drying rolls 2, 3, 4, 5, 6 and 7 in the order named, the last mentioned roll being the issuing roll. In the present instance, I have shown my hood indicated at 8, surrounding the upper portion of the roll 5 being the third from the last. It is preferably a metal hood closely encompassing the roll down to or below the shaft 9 thereof. The front or end of the hood or cover is fitted with a door 10 which may be raised while threading in the sheet of paper or for inspection purposes. The hood fits so closely that only a small amount of outside air can come under it though it is necessary that a little air be allowed to pass over the sheet as it traverses the drying roll in order to supply a current to the psychrometer.

A pipe 11 is connected to the center of the hood 8 and leads therefrom to a housing 12 from which the air and vapor drawn from the hood is discharged as indicated by the arrows under the influence of a fan or blower located at 13, the function of which latter is merely to cause a circulation and draw off the accumulation within the hood. The psychrometer before mentioned is arranged in the casing 12 and is affected by the air and the vapor from the hood 8 which rises from the web of paper passing thereover said web being indicated at 14. Inasmuch as the hood covers the entire roll and the entire web passing over the same, it accumulates the evaporation of the paper along its entire width and over a considerable surface thereof that is in contact with the drying roll so that an accurate average vaporization of the particular temperature at which that drying roll is running is accumulated and recorded. The hood may be placed on any one of the rolls but one of the last ones, such as the roll 5, is preferable.

A psychrometer such as that referred to is well known in the art, and for this reason has not been shown in detail. It is shown in a general way in Figure 1, and consists of a wet bulb and a dry bulb arranged side by side. The wet bulb, indicated at 14, is covered by a wick 15 extending into a reservoir 16 supplied by a pipe 17. Tubes 18 and 19 run therefrom to a recording device 20 having arms or pencils 21 and 22 connected respectively to the two bulbs to show the ratio between the temperature and the humidity.

In Figure 2 is shown a modification of the hood 8 which is marked 8^a and is shown to entirely surround the drying roll 5. The roll being thereby made more or less inaccessible, feed rolls 23 are provided to carry the paper into the hood, these feed rolls being driven by a sprocket 24 from the shaft 9. At the

point at which the web emerges a doctor blade 26 is provided to insure the passage of the web out through an opening 27.

The difference between these wet and dry bulbs in temperature gives at once the approximate moisture content of the air in the hood. Now it has been found by experimenting that if the sheet running over the dryers is kept at approximately the same 10 caliper, furnish, speed and all other factors are as efficient as possible, the amount of water in the sheet will vary directly as the difference between the wet and dry bulb temperatures. Of course, this difference in temperature of the two thermometers is found 15 to be characteristic for different classes of paper also. Hence if the relative humidity can be established for a given caliper and furnish, the moisture content of the sheet 20 can be established so that the relative humidity indicates the exact moisture content of the sheet as it passes over that particular dryer or set of dryers. These recording thermometers, are, of course, purchasable in 25 the market and are easily attached to the machine and the motor and fan are added in order to direct the air from within the hood or surrounding drum over the two temperature bulbs.

30 Referring again to the embodiment of the invention shown in Figure 1, a feed roller 30 is preferably mounted in the hood to rest on top of the drying roll 5. This is to facilitate threading the paper through the roll as 35 the door that gives access to the interior of the hood is relatively small and it is advantageous to have a positive feed roll to which the paper can be threaded through the door and thence be sure of passing around 40 the dry roll and emerging at the bottom of the hood on the other side.

This equipment can be attached to a machine at a very low cost and for economy of operation and in savings it cannot be equalled 45 by any other machine known to me for obtaining the moisture content of the paper as it is being made. With its use the operator is given information on such factors in producing a good sheet of fibre consistency, 50 correct freeness of the stock, condition of the belts, the efficiency of the press rolls, the proper working of dryers and ventilation systems and other important things that may make or unmake a good sheet of paper, and 55 all of which are reflected in the moisture content at the delivery end of the machine. Such information hitherto has been obtainable only by carefully watching each.

I claim as my invention:

60 1. In a paper making machine, the combination with a heated drier over which the paper web continuously travels, of a hood extending transversely widthwise of the web from side to side and adapted to trap the 65 vapor issuing from a complete section of the

web while on the roll, and a psychrometer embodying wet and dry bulbs exposed to the action of such vapor.

2. In a paper making machine, the combination with a heated drier over which the paper web continuously travels, of a hood extending transversely widthwise of the web from side to side and adapted to trap the moisture issuing from a complete section of the web, while on the roll, a psychrometer embodying wet and dry bulbs and means for driving a current of air through the hood and into contact with the wet and dry bulbs of the psychrometer. 70

3. In a paper making machine, the combination with a plurality of drying rolls, of means for trapping the vapor issuing from the paper web as it passes over a given one of said rolls, a psychrometer embodying wet and dry bulbs, and means for conducting the vapor arising from said roll into contact with the wet and dry bulbs of the psychrometer. 75

4. In a paper making machine, the combination with a plurality of drying rolls, of a hood encompassing one of said rolls and adapted to trap the vapor issuing from the web as it passes over said roll, a psychrometer embodying wet and dry bulbs, and means for conducting the vapor arising from said roll into contact with the wet and dry bulbs 90 of the psychrometer. 95
